UNITED STATES PATENT OFFICE.

CHARLES A. BRAUNGER, OF ELIZABETH, NEW JERSEY, ASSIGNOR OF ONE-HALF TO
JAMES HENRY PRUITT, OF CISSNA PARK, ILLINOIS.

MISSILE THROWER.

Application filed July 15, 1921. Serial No. 485,058.

To all whom it may concern:

Be it known that I, CHARLES A. BRAUNGER, a citizen of the United States, and a resident of Elizabeth, in the county of Union and 5 State of New Jersey, have invented a new and Improved Missile Thrower, of which the following is a full, clear, and exact description.

This invention relates to a missile thrower 10 primarily designed for throwing bombs or the like.

Prior to this invention the usual method of throwing bombs was by hand or by the use of a rifle. In throwing bombs by hand 15 the range is very limited and at the extreme range there is little accuracy. When rifles are used for throwing bombs it is necessary to carry attachments to be used in conjunction with the bombs and this is unsatisfactory under service conditions. Further, throwing bombs by means of a rifle is very injurious to the rifle.

The object of this invention is to provide a simple and compact bomb thrower which 25 increases the range at which bombs may be effectively used and which gives great accuracy in the throwing.

These and other objects of the invention will be more clearly understood from the 30 following detailed description and accompanying drawings.

Figure 1 is a cross section through the bomb thrower and bomb, showing the bomb placed on the guiding means; and

35 Figure 2 shows a modification of the bomb thrower.

Referring to the above-mentioned figures, a recoil tube 10 is slidably mounted on a block 11 which is fixed to the hand grip 40 casing 12. A slot 13 which fits over the hand grip casing 12 is provided in the recoil tube 10 so as to allow it to slide on the block 11. An opening 14 extends through the block 11 and an enlargement 15 of the 45 opening 14 is made at the rear end of the block 11. Integral with the recoil tube 10 is a projection 16 which is of smaller cross section than the recoil tube. An opening 17 which is in alignment with the opening 14 50 in the block 11 extends through the projection 16. A firing pin 18 having an enlarged head 19 projects through the openings 14 and 17 which serve as bearings for the firing pin to slide in. The enlarged head 19 of the 55 firing pin 18 slides in the enlarged opening

15. A spring 20 is provided in the recoil tube 10 which abuts against the front portion of the recoil tube and fits over a projection 21 on the block 11.

The firing pin is operated by a hammer 39 60 which constitutes part of the manually actuated action described in my co-pending application, Serial No. 485,057, filed July 15, 1921, entitled manually actuated action for firearms. Any other action may be used to 65 operate the firing pin. The action mentioned above is only one of the preferred forms that might be used in conjunction with my bomb thrower.

In the manually actuated action shown, 70 the hammer 39 is pivoted at 21, and a trigger 22 pivoted at 23 is provided with a spring-controlled latch member 24 which serves to hold the trigger and hammer in engagement during the cocking action, and which releases the hammer from the trigger on the completion of the cocking action. The arm 25 of the spring mounted on the projection 26 of the hand grip chamber cooperates with the hammer 39 and serves to rotate the hammer forward after it is released from the trigger 22. The strength of the stroke of the hammer is increased by means of a piston 27 which is projected forward by a spring 28, that is energized during the 85 cocking action of the hammer.

The projection 16 may be of any cross section but the preferred form is circular. The cross section at the base may be larger than the cross section at the outer end thus 90 giving the projection the form of a conic frustum if the cross section is circular. This is not essential but is only one form that the projection may have. This projection serves as a carrying and guiding means 95 for the missile to be thrown. The bomb to be thrown has a shell 29 in which a charge 30 is placed. Projecting into the bomb 29 is a tube 31, the base of which has a socket 32 which slides over the projection 16. Located just in front of the socket 32 in the tube 31 is a revolver cartridge or some other charge 33. This charge has a detonator 34 which is in striking distance of the pin 18.

The operation of this device is as follows: 105

The trigger 22 is drawn back a slight distance rotating the upper part of the hammer backward. This allows the firing pin 18 to be moved backward a short distance so that its point does not extend beyond the end of 110

the projection 16. The bomb 29 which has the tube 31 fastened therein is then placed upon the projection 16. This projection just fits the socket 32 in the tube. Every-
5 thing is in readiness for the firing and throwing of the bomb. The trigger is then drawn to complete the cocking operation of the hammer, which is then released and rotated forward striking the firing pin and
10 forcing it against the detonator in the cartridge 33. The force of the explosion of the charge in the cartridge 33 propels the bomb which is guided by means of the projection 16 and the socket 32 which cooperates with
15 the projection. The back blast of the explosion against the recoil tube is taken up by means of the recoil spring 20.

The distance the bomb may be thrown will depend upon the angle at which the
20 bomb thrower is held. After a couple of experiments a bomb may be directed with considerable accuracy. The maximum range will depend to a certain extent upon the propelling charge used.

25. A modification of the recoil absorbing means is shown in Figure 2. In this case a tube 35 is fastened to the hand grip casing 12 and the piston 36 is slidably mounted in the tube 35. A spring 37 is introduced between the back of the tube and the shoulders of the piston to act as a recoil spring. The automatic action is the same as shown in Figure 1 except in this case no auxiliary spring 28 is supplied and the hammer 39
30 may be either exposed or enclosed in a casing. The projection 16 which serves as a guiding means is integral with the piston.

Claims.

1. A missile projector including a casing,
40 a recoil tube slidably mounted on the casing, means for guiding the flight of the missile carried by the recoil tube, a firing pin slidably mounted in the recoil tube, and a man-

ually actuated action for operating the firing pin located in the casing.

2. In a device for throwing missiles, comprising means for supporting the missile external to the missile projector and for directing its flight, a recoil means associated with the supporting and directing means, manually operated firing means provided in conjunction with said supporting means, in operative relation with the missile to fire the propelling charge carried by the latter.

3. A missile projector comprising a hand grip casing, a recoil tube slidably mounted on the hand grip casing, missile guiding means carried by the recoil tube, a firing pin slidably mounted in the recoil tube and guiding means, a manually actuated hammer for operating the firing pin, and a spring controlled plunger slidably mounted in the recoil tube in alignment with the firing pin for projecting the hammer against the firing pin.

4. A missile projector including a casing, a tube slidably mounted on said casing, a recoil spring interposed between the tube and the casing, normally retaining the former in its forward position, missile guiding means mounted on the forward end of the tube, a firing pin slidably mounted in the tube and guiding means, and manually actuated means mounted in the casing for operating the firing pin.

5. A missile projector including a hand grip casing, a tube slidably mounted on the hand grip casing, a recoil spring interposed between the tube and hand grip casing, missile guiding means carried by the tube, a firing pin slidably in the tube and guiding means, and manually actuated means for operating the firing pin located in the hand grip casing.

CHARLES A. BRAUNGER.
